APPARATUS FOR THE HANDLING AND DEVELOPING OF MOTION PICTURE FILMS

Cuno Bryant, Multnomah County, Oreg.

Application July 10, 1940, Serial No. 344,745

1. Claim. (Cl. 95—93)

My present invention relates to an apparatus which may be employed for handling motion picture films during the developing and drying processes. Due to the length of a motion picture film, its tendency to stretch upon absorbing moisture during the developing, fixing and washing processes, and due to the fragility of the film during said processes, it becomes desirable to provide means for handling the film, which minimize as far as possible all strains upon the film and also permit the normal stretching and shrinking of the film during the developing and drying processes.

It is an object of my invention to provide a film handling device which will enable a single operator to handle the same, without the aid of light, except when light is desired, from the start of the developing processes to the conclusion of the washing process.

Another object of my invention is to provide a device which permits the normal expansion and contraction of the film without placing any undue strains upon the same.

A further object of my invention is to provide a simple and inexpensive film developing apparatus by which a minimum quantity of developing and fixing solutions will be required in connection with the processes of developing, fixing and washing of the film.

Other objects of my invention are to improve the means by which the motion picture film, in the processes of developing, is moved from one chemical tray to another, or to and from a washing solution without the necessity of moving any of said trays and thereby avoiding the loss of solution and injury to the film caused by the slopping of the solutions from their respective trays.

Referring to the drawings:

Fig. 1 is a plan of the film developing apparatus.

Fig. 2 is a side elevation of said apparatus with the carriage track lowered.

Fig. 3 is a fragmentary side elevation with the carriage track raised and with a drying reel placed in position to take the developed film.

Fig. 4 is a longitudinal section taken along the line 4—4 in Fig. 1.

Fig. 5 is a cross section taken along the line 5—5 in Fig. 1.

Fig. 6 is a cross section taken along the line 6—6 in Fig. 1.

Fig. 7 is a section taken along the line 7—7 in Fig. 1.

Fig. 8 is a section taken along the line 8—8 in Fig. 1.

Fig. 9 is a front elevation of the drying reel, 93.

Fig. 10 is a fragmentary elevation of the drying reel along the line 10—10 in Fig. 9.

No. 45 is a tank covered with a suitable black acid resistant paint and is supported by side members 16, 17, 18 and 19 and the end members 20, 21, 22 and 23, and bottom slats 24 upon the 10 pairs of legs 25 and 26. At one end of the tank there is an inlet 27 to permit water to flow in through this tank to the outlet 28 which regulates the water level within the tank. Connected to the bottom of this tank is a drain 29 with the valve 30 for completely draining said tank through the pipe 31.

Within the tank are a number of chemical trays 32, 33, 34 and 35 coated with black acid resistant paint for holding chemicals used in the 20 development of the film. These trays are held in position by a number of lugs 36 attached to the side of the tank.

The chemical trays are so constructed as to permit the flow of water to contact their sides 25 and bottoms, thus maintaining the chemicals within these trays at a constant determined temperature.

Secured to the legs 25 and 26 and riding vertically up and down on them are the vertical 30 supports 37, 38, 39 and 40, connected at their lower ends by cross bars 41 and 42 anchored thereto by means of plates 43, 44, 45 and 46. These plates overlap the edges of the legs in a manner that allows them to ride up and down on 35 said legs. The upper ends of the members 37 and 38 support the cross member 47 and the members 39 and 40 support another cross member 48. These members 47 and 48 correctly space the two longitudinal tracks 49 and 50 and are 40 rigidly attached thereto. The tracks 49 and 50 can be raised and lowered by an adjustable pulley and lever system composed of the pulleys 51, 52 and 53. Threaded through these pulleys is a 45 flexible wire system 54 complete with turn buckles 55, 56 and 57 for correctly controlling the lifting tension.

A piece of flexible wire has one end attached to the cross bar 41 and the other end connected with the lower portion of the turn buckle 57. Another piece of flexible wire connected with the upper portion of the turn buckle 57 passes over the pulley 52 and connects with the lever 58, then passes over the pulley 51 and connects with one end of the turn buckle 55. Another 55 piece of flexible wire connected with the other

end of the turn buckle 55 passes over the pulley 53 and connects with the upper end of the turn buckle 56, and a similar piece of flexible wire is connected with the lower end of the turn buckle 56 and has the other end thereof attached to the cross bar 42. The cross bars 41 and 42 have springs 60 and 61 to maintain a proper tension and to assist in the riding of the track system to its lower position.

Riding on the tracks 49 and 50 is a carriage 62 which is supported by rollers 63 at all four corners, making the positioning of the carriage easy.

Centering in the journals 64 and 65 is the shaft 66 to which is attached the drum 67. To one end of this shaft is affixed a large pulley wheel 68 which is driven by the endless belt 69. The other end of this belt is attached to the pulley 70 which is in turn affixed to the driving motor 71. On the pulley wheel 68 are affixed two bumpers 72 and 73 centered behind the small shaft 74 on which journals the hammer 75.

When the pulley wheel 68 is in motion, the hammer 75 will be thrown against the bell 76, thus informing the operator that the wheel 68 is not slipping.

The motor is controlled by the switch 77 through the conduit 78. Also attached to the carriage 62 is a dark room type of shielded lamp 79 which can be moved to any horizontal position by its movable shaft 80, which in turn can be adjusted to any desirable height by a thumb screw 80'.

Also attached to the carriage 62 is the shaft 81 upon which can be mounted a film reel 82. This film reel journals freely on said shaft 81 and slides freely from one end to the other of said shaft.

To the end of the shaft 81 is attached a clothes pin or other suitable clamping device 83 which will keep the reel from coming off the end of the shaft. The drum 67 has a continuously ribbed surface 84 which properly spaces the film 85 as it is wound on said drum. The end of the film is attached to a piece of adhesive material 86, the other end of which adhesive material is attached to a flexible spring 87 adapted to loop the hook 88 on the drum 67.

In actual operation, when the film is wound upon the drum, the spring 87 is stretched out to considerable length. This is done for the reason that the film undergoes a considerable stretching action when moistened and, as the drum is rotated carrying the periphery of the drum and the film through the developing solution, any stretching of the film is taken up along the surface of the drum toward the end which is attached to this spring, which compensates for the change in length of the film occurring during the process of developing.

In the practice of film developing, with this device, the film having been wound upon the drum with the track in its topmost position and holding said drum clear of the tank and trays, the drum can then be positioned at any place along this track and centered in that position by means of the bolt 89 which locks through any one of the five variously positioned angles 90 along the side of the track 50. In this manner it is easy to correctly center a drum with its film above any of the trays 32, 33, 34 and 35 or the central space 91 which is used for washing chemicals off of the film after its bath in one of the chemical trays. The whole assembly can then be lowered to its operating position.

5 Adjacent to the motor switch 77 is a small rotary switch 92 which controls light 79. There is also a reel 93 composed of fixed dowels 94 and movable dowels 95 which are retained within the elongated slots 96. Tension means at each end of the movable dowel 95 holds said dowel outward from the axis of said drum. This means as shown in Fig. 10 consists of an endless wire spring 97 which loops under the movable dowel 95 adjacent the inner face of the reel side, extends over the outer circumference of said reel side and loops again under the outer end of the movable dowel 95. The tension of the wire spring 97 is exerted against the under side of the movable dowel 95. This is done to allow shrinkage 10 of the drying film to be taken up against spring tension.

15 The reel 93 is mounted on a shaft 98 which in turn journals in the supports 99 mounted on the base 100 which can be placed across the track members 49 and 50 and held in position by the spacers 101 and 102.

20 103 are radiating fins or vanes which are adapted to catch a directed current of air causing the reel 93 to revolve during the process of 25 drying the film.

25 In using my improved film developing apparatus, a person working alone in a dark room, and without the aid of artificial light, may readily attach the film for winding upon the drum by 30 looping the flexible spring 87 over the hook 88 on the drum 67, wind the same upon the surface of said drum between the ribs 84, and attach the other end of the film to the surface of the drum with a piece of adhesive material, whereupon 35 the drum may be quickly centered or located, over the desired tray and lowered to its position for developing so that a portion of the drum's surface and the film thereon will be submerged in the developing solution. The rotation of the drum causes all portions of the film, in order of sequence, to be so submerged and thereby guarantees a complete and uniform development of the film.

35 In Fig. 3, the reel 93 is shown positioned upon the carriage track a short distance from the drum 67 and in position so that the film after going through the various developing and washing processes may be wound on to the drying reel 93 directly from the drum 67.

40 50 In an alternative construction, the drying reel 93 may be carried by the shaft 66 in lieu of the drum 67 in which case the reel 93 will carry the film during the developing, fixing and washing processes in lieu of the drum 67.

45 55 When the reel 93 is used during the developing, fixing and washing processes, in lieu of the drum 67, both the stretching of the film during the developing processes and the shrinking of the film during the drying process are taken care 60 of by the movable dowels 95.

65 70 I realize that various means have heretofore been provided for developing, fixing and washing motion picture films by what is known as a continuous process where the film itself moves from one solution to another so that one portion of the film may be in one compartment at the same time that another portion of the film is in another compartment. This process of developing requires complicated and expensive equipment and the use of a large volume of chemical solutions which make the processes impracticable for individual use, or for use other than where a large quantity of films are being developed. 75 My improved developing apparatus also elimi-

nates breakage and injury to the film caused by the strain upon the same in what is known as the continuous process of developing.

I do not claim broadly, means for developing motion picture films in which a plurality of containers for chemical solutions are used or in which a tray containing one solution may be removed and replaced by a tray containing another solution.

What I claim is:

In a motion picture film developing machine, a water tank containing a plurality of chemical

trays so arranged as to permit the water in said tank to contact a large portion of the outer surface of said chemical trays, a drumlike film holder adapted to rotate with a portion of its film bearing surface submerged in a solution in any selected chemical tray, a movable carriage support for said drumlike film holder, a track for said carriage, and means for raising and lowering said track to permit the moving of the film holder from one tray to another.

CUNO BRYANT.
